MACHINERY TO BE EMPLOYED IN THE DOUBLING OR FOLDING OF METALLIC PLATES
OR SHEETS.

Application filed October 6, 1927, Serial No. 224,421, and in Great Britain October 21, 1926.

This invention relates to machinery to be employed in the doubling or folding of metallic plates or sheets as for example the machinery employed in the manufacture of tin plates whereby the preliminary doubling or folding operations are performed for obtaining from the pieces or bars of steel what are technically known as "black plates."

The present invention has for its object 10 the provision of improved machinery or mechanism whereby the said operation of doubling or folding metallic plates or sheets by the application of endwise pressure can be carried into effect.

15 The invention consists of improved machinery to be employed in the doubling or folding of metallic plates or sheets embodying inwardly moving and pivotally mounted members adapted to exert end pressure on the 20 plates or sheets, said members preferably being in the form of pendulum-like members adapted for mechanical oscillation and preferably co-operating with a mechanically operated lifting member the operation whereof 25 is synchronized with that of the pendulum-like members whereby subsequent to the folding or doubling of the plate or sheet the said lifting member is brought into operation to feed the doubled or folded plate or sheet to 30 a pair of lifting rolls, which effect the completion of the doubling of the plates or sheets and the direction of the doubled plates or sheets to a pair of transfer rolls which in turn direct the plates or sheets to a collecting tray or other mechanisms. The invention also resides in the provision in conjunction with the pendulum-like members of 35 pivotally mounted pressure plates adapted to apply pressure to the partially doubled or folded plates for effecting a further doubling or folding operation on the plates or sheets. The invention further resides in the provision of an adjustable platform for permitting of a variation in the amount of overlap to 40 be given to the plates or sheets when doubled or folded. The invention still further resides in the provision of an adjustable side guide for preventing lateral displacement of the plates or sheets during the doubling or folding operation. The invention also resides in 45 the details of construction and in the doubling or folding machine as a whole.

The invention will now be described with

particular reference to the accompanying sheet of drawings, wherein:

55

Figure 1 is a part sectional front elevation of a doubling or folding machine constructed in accordance with the invention and illustrating the pendulum-like members in their outermost position with a plate or sheet 60 in position in readiness for a doubling or folding operation the structural steel work for supporting the machine being shown in chain line.

60

Figure 2 is a similar view to Figure 1 with 65 the pendulum-like members shown in the position they occupy at the completion of a doubling or folding operation, and

65

Figure 3 is an end elevation of the machine in the position seen in Figure 2.

70

In the drawings like numerals of reference indicate similar parts in the several figures.

A pair of bar members 4 are secured adjacent their upper ends on spindles 5 rotatably mounted in bearings carried by a supporting framework 6. Bolted to the lower portions of the rear faces of each of the bars 4, which may be regarded as constituting pendulum-like members, and spaced therefrom by distance pieces 7^a, is a guide plate 7 the space obtaining between the inner face of the guide plate and the rear face of the members constituting a guide-way for a sliding block 8. The said blocks 8 are each provided with 75 trunnion-like pins 9 which project on either side of the blocks 8 and have connection with a pair of continuous roller driving chains 10 there being two chains 10 to each pendulum-like member 4 disposed one on either side of 80 the said members 4. Each chain 10 passes around four rotatably mounted sprocket wheels 11^a, 11^b, 11^c, 11^d respectively so arranged that each chain 10 follows a trapezium-like path the outermost pairs of sprocket 85 wheels 11^a and 11^b having their axles disposed in a plane which is parallel to the longitudinal axis of the respective pendulum-like member 4 when the said member is in 90 its outermost position as seen in Figure 1. The innermost pairs of sprocket wheels 11^c and 11^d have their axles disposed in a plane which is inclined away from the vertical axis of the machine as a whole. One pair of chains 10 is driven from a common driving shaft 12 95 through a pinion gear 13 and 14 and the other 100 through a pinion gear 13 and 14 and the other 105

pair of chains is driven from the main driving shaft through a chain 15.

Pivotedly mounted in the upper portion of each bar-like member 4 is a shaft 16 to which is secured a pressure plate 17 of substantially rectangular shape said plates being disposed on the inner sides of the bar-like members 4. Also secured to the aforesaid shafts are rearwardly extending arms 16^a on which are mounted balance weights 16^b which normally tend to rotate the shaft 16 and move the pressure plates 17 inwardly towards one another.

Disposed intermediate the two pendulum-like members 4 and adapted to reciprocate in a vertical plane is a bar-like lifting member 18 the upper end whereof is formed of a spear-like shape the base of the blade-like portion 18^a whereof terminates in a pair of laterally extending horizontally disposed shoulders 18^b which in the normal position of the lifting bar 18 are located in the plane containing the edges of the undoubled plate or sheet 20 when placed in position in the machine for doubling said blade-like portion 18^a serving to cause the plate or sheet to take an upwardly curved or cambered form or to increase the normal arched or cambered form of the plate or sheet when the plate or sheet is placed in the machine in readiness for doubling or folding.

The lower section of the bar-like lifting member 18 is provided with an elongated slot 18^c in the lower portion whereof is rotatably mounted a pulley 21 around which passes a rope 22 the intermediate portions whereof pass around pulleys 23 disposed on either side of the lifting bar said rope having weights 24 attached to the ends thereof. The pulleys 23 around which the intermediate portions of the rope 21 pass are mounted on spindles supported in bearings carried by hangers 25 depending from the framework 6. The bar-like lifting member 18 is provided intermediate its ends with a pair of parallel laterally extending arms 26 which are disposed in the path of the trunnion-like pins 9 on the blocks 8 when the said pins 9 are traversing the outwardly inclined sections of the chain path so that when the said pins 9 are traversing the said section of the path they bear on the underside of the arms 26 and raise the bar-like lifting member 18, the said member 18 automatically falling to the lower position upon the passage of the pins 9 to the outward and horizontal sections of their travel the weights 24 permitting of this movement obtaining without undue shock to the machine. The upper portion of the bar-like lifting member 18 is formed with a slot 18^d within which engages a rectangular guide block 28 secured to the framework 6 said block 28 in conjunction with the slot 18^d serving to ensure the true vertical motion of the said lifting member.

The plate 20 to be doubled is placed upon a pair of platforms 29, 30 respectively which are inclined downwardly towards the centre of the machine said platforms being disposed at a level substantially as that containing the centres of the pendulum-like members 4 when in their outermost positions. The platform 29 is hingedly connected adjacent each corner to links 31 which in turn are fixed to spindles rotatably mounted relatively to the fixed framework 6, the spindle fixed to the rearmost pair of links preferably having attached thereto a lever 32 provided with a positioning plunger adapted to co-operate with a plurality of holes 33^a formed in a quadrant 33 whereby the angle of inclination of the platform 29 relatively to the other platform 30 may be varied for the purpose of permitting of an adjustment of the amount of overlap to be given to the plates or sheets subsequent to the folding or doubling operation.

In order to preserve the position of the plate during a doubling operation there are disposed on each side of the machine guide plates 34 and 35 respectively consisting of strips of sheet metal bent to a segmental shape one of these guide plates 34 being carried by a bracket 36 adjustably mounted relative to the framework. The other guide 35 is fixed to a bracket 37 mounted on one arm 95 of a bell crank lever 38 the other arm whereof is provided with an inclined track 39 which co-operates with a rotatably mounted roller 40 carried by one of the pendulum-like members 4, the said roller 40 being adapted to ride on the surface of the inclined plane as the pendulum-like member carrying the roller approaches its innermost position. The arm of the bell crank lever carrying the guide is anchored to one end of a coil spring 105 41 the other end of which is attached to a bracket fixed to the framework 6.

Disposed above the pendulum-like members 4 are a pair of lifting rolls 42 the nip whereof is disposed in the plane containing the vertical axis of the machine the lifting rolls serving to receive the folded or doubled plate and to complete the folding or doubling operation and also to pass the doubled or folded plates either to a pair of transfer 110 rolls which in turn direct or pass the sheets to a collecting platform or to a shearing or other mechanism.

The operation of the machine is as follows:—

The plate 20 to be doubled is placed on the oppositely inclined platforms 29, 30 when the pendulum-like members 4 are in their outermost position, see Figure 1. The angle of inclination of the movable platform 29 is then adjusted by means of the lever to give the desired amount of overlap in order to avoid unnecessary wastage and the adjustable guide 34 set so that the guides 34 and 35 are spaced a slightly greater distance 130

apart than the width of the plate 20 whereby undue friction on the plate during the initial stages of the doubling or folding operations is prevented. The driving shaft 12 is then caused to rotate and thereby to effect the travel of the chains 10 about the sprockets 11^a, 11^b, 11^c and 11^d the right hand pair of chains 10 rotating in a clockwise direction and the left hand pair of chains 10 in an anti-clockwise direction. When the pins 9 connected to the slide blocks 8 are following the section of the chain paths disposed parallel to the pendulum-like members 4 when in the outermost position it will be understood that no oscillation of the pendulum-like members 4 will be involved as the slide blocks 8 will merely partake of a sliding motion in their guideways. Upon the pins 9 on the chains entering the lower horizontal section of the chain path in which section the pins 9 travel towards the centre of the machine the pendulum-like members 4 are drawn towards one another and thereby caused to exert pressure on the ends of the plate or sheet 20 and to effect a doubling or folding thereof. This doubling or folding proceeds until the pendulum-like members 4 approach one another whereupon the partially doubled or folded plate or sheet comes into contact with the pressure plates 17 pivotally mounted in the upper portion of the pendulum-like members 4 and as the said members come closer together the pressure plates 17 align themselves to the plate 20 by reason of their pivotal mounting and effect the completion of the doubling operation. As the pendulum-like members 4 approach their innermost positions the member 4 carrying the roller 40 causes the said roller to ride on the inclined plane 39 whereby the bell crank lever 38 is caused to turn about its pivot to move the guide 35 inwardly into contact with the edge of the plate and to move the plate into contact with the guide 34 thus preserving a correct alignment of the plate in order to ensure a true line of fold during the final doubling or folding operation. When the pendulum-like arms are in their innermost positions the pins 9 on the chains commence to move into the upward and outwardly inclined sections of their path whereby the blocks 8 are caused to move away from the centre of the machine thereby effecting a slight opening motion of the pendulum-like members 4. Simultaneously with this opening movement of the pendulum-like members the pins contact with the underside of the arms 26 on the bar-like lifting member 18 and carry the said bar vertically upwards whereby the blade-like portion 18^a of the said member engages between the lower ends of the folded plate or sheet so that the lower edges thereof rest on the shoulders 18^b at the base of the said blade portion and as the member 18 is moved vertically upwards the now folded plate or sheet 20 partakes of the same motion until ultimately it is directed into the nip of the lifting rolls 40 which in turn co-operate with the transfer rolls which direct 70 the plate or sheet to a collecting platform or to a conveyor or to a shearing or other mechanism.

It will be appreciated that by reason of the slight opening movement of the pendulum-like member 4 which obtains prior to and during the raising of the lifting member 18 the tendency to a buckling of the plate which would normally occur is avoided. Further, the guides 34 and 35 at each side of the machine permit of the adaptation of the machine to various sizes of plates or sheets and also prevent the lateral movement of the plate or sheet during the folding or doubling operation. 85

A doubling or folding machine as hereinbefore described is efficient in operation and capable of continuous operation with a minimum of attention. 90

What we claim is:—

1. Machinery to be employed in the doubling of metallic plates comprising pendulum-like members, means for oscillating said pendulum-like members in opposite directions whereby the said members on their inward motion may exert end pressure on the plates and effect a doubling thereof, a pair of lifting rolls, a mechanically operated lifting member, means for synchronizing the operation of the said lifting member with that of the pendulum-like members whereby subsequent to the doubling of the plate the lifting member is brought into operation to feed a doubled plate to the said lifting rolls. 95
2. Machinery to be employed in the doubling of metallic plates comprising a fixed framework, a pair of pendulum-like members pivotally mounted relatively to said framework, a power source, endless driving chains having connection with said pendulum-like members and adapted to be driven from said power source, said chains effecting an opposed oscillation of the pendulum-like members whereby end pressure is exerted on the plates for effecting a doubling thereof on the inward motion of the said members. 105
3. Machinery to be employed in the doubling of metallic plates comprising a fixed framework, a pair of pendulum-like members pivotally mounted relatively to said framework, a guideway formed in each of the pendulum-like members, a sliding block mounted in each guideway, a power source, endless driving chains adapted to be driven from said power source and means for connecting said blocks to the driving chains, said chains effecting an opposed oscillation of the pendulum-like members whereby the said members on their inward movement are caused to exert end pressure on the plates to be doubled. 110

4. Machinery to be employed in the doubling of metallic plates comprising a fixed framework, a pair of pendulum-like members pivotally mounted relatively to said framework, a plurality of sets of sprockets the axles of each set whereof are arranged in a trapezium-like form so that the planes containing the axles of the outermost sprockets are disposed parallel to the respective pendulum-like members when in their outermost positions and the axles of the innermost sprockets located in planes inclined outwardly and upwardly from the central axis of the fixed framework, endless driving chains adapted to 10 pass around said sprockets, means for connecting the pendulum-like members to said driving chains and means for effecting the rotation of said sprockets whereby the endless driving chains connected to the one pendulum-like member are constrained to move in an opposite direction to the chains connected to the other pendulum-like member so that the said chains effect an oscillation of the pendulum-like members and cause the said members 20 on their inward movement to exert end pressure on the plates for effecting a doubling thereof.
5. Machinery to be employed in the doubling of metallic plates comprising a fixed framework, a pair of pendulum-like members pivotally mounted relative to said framework, a plurality of sets of sprockets the axles of each set whereof are arranged in a trapezium-like form, endless driving chains adapted to pass around the sets of sprockets, means for connecting the pendulum-like members to the respective endless chains, means for effecting the rotation of the sprockets whereby the said chains are caused to effect an opposed oscillation of the pendulum-like members, a lifting member, projections on said lifting member, means on said chains for contacting with the projections on the lifting member when the endless chains are travelling in the 30 innermost portion of their paths, and a plate-like portion at the upper end of said lifting member for giving to the plate a doubled and arched form or camber when the plate is placed in the machine in readiness for a doubling operation.
6. Machinery to be employed in the doubling of metallic plates comprising a fixed framework, a pair of pendulum-like members pivotally mounted relatively to said framework, pressure plates pivotally mounted in the upper portion of said pendulum-like members, counterbalancing means for said pressure plates for causing the said plates to align themselves readily to the plate to be doubled during a doubling operation, a plurality of sets of sprockets mounted in the said framework, endless driving chains adapted to be passed around said sprockets, means for connecting said pendulum-like members to said driving chains, means for 40 effecting the rotation of said sprockets whereby the chains are caused to effect an opposed oscillation of the pendulum-like members, a fixed platform for supporting one end of the plate to be doubled, an adjustable platform for supporting the other end of the plate to be doubled the adjustment provided serving to control the amount of overlap to be given to the doubled plate, a pair of lifting rolls, a lifting member, a blade-like upper portion on said member for giving the plate an initial arched or cambered formation, projections on said lifting member and means on said endless chains for effecting a lifting of the said member when the said means are 50 traversing the innermost portions of the chain paths.
7. Machinery to be employed in the doubling of metallic plates comprising a fixed framework, a pair of oppositely acting pendulum-like members pivotally mounted relatively to said framework, a plurality of sets of sprockets, endless chains adapted to pass around said sets of sprockets, means for connecting the pendulum-like members to said chains, a power source, means for rotating the sprockets from said power source, a fixed platform secured to said framework and adapted to support one end of the plate to be doubled, an adjustable platform adapted to support the other end of the plate to be doubled, an adjustable guide for one side of the plate to be doubled for maintaining the correct position of the plate during the doubling operation, a guide for the other side of said plate, means for bringing said last mentioned guide into operation during the later stages of the doubling operation only, a lifting member, a pair of lifting rolls, means for effecting the lifting of the said lifting member subsequent to the completion of the doubling operation whereby the doubled plate is fed to the lifting rolls and means for counterbalancing the said lifting member.
8. Machinery to be employed in the doubling of metallic plates comprising a fixed framework, pairs of pendulum-like members pivotally mounted relatively to said framework, pairs of endless driving chains adapted to rotate in opposite directions, means for driving said chains, means for connecting said members to said chains, a pair of feed rolls, a lifting member for effecting the raising of the doubling plate to said rolls, means for lifting said member subsequent to the attainment by said pendulum-like members of their innermost positions, means for effecting a slight outward movement of the pendulum members prior to the actuation of the said lifting member, pressure plates pivotally mounted in the upper portion of the said pendulum-like members, a fixed platform for supporting one end of the plate to be doubled, an adjustable platform for supporting the other end of the plate to be doubled, an ad- 100
- 110
- 120
- 130

justable guide for preserving the position of one side of the plate to be doubled, a guide for the other side of the plate to be doubled, means for bringing the last mentioned guide into operation only at the later stages of the doubling operation and a plate-like portion of the said lifting member for giving an

initial arched or cambered formation to the plates to be doubled prior to the commencement of the doubling operation.

10

In testimony whereof we have signed our names to this specification.

HUBERT SPENCE THOMAS.

WILLIAM ROBERT DAVIES.
